UNITED STATES PATENT OFFICE

152,322

DESIGN FOR A VEHICLE TRAILER

Edward Chapin, Buffalo, N. Y.

Application May 8, 1947, Serial No. 138,904

Term of patent 14 years

(Cl. D14—3)

To all whom it may concern:

Be it known that I, Edward Chapin, a citizen of the United States, residing at Buffalo, in the county of Erie and State of New York, have invented a new, original, and ornamental Design for a Vehicle Trailer, of which the following is a specification, reference being had to the accompanying drawing, forming part thereof.

In the drawing:

I claim:

The ornamental design for a vehicle trailer, as shown.

EDWARD CHAPIN.
